FOLDING CHAIR

Oscar Löwenherz, Brussels, Belgium, and Martin Behrens, Cologne, Germany

Application August 29, 1938, Serial No. 227,445
In Germany October 22, 1937

1 Claim. (Cl. 155—117)

Our invention relates to folding chairs and to means for locking coacting parts of such chairs in different relative positions.

It has particular reference to that type of folding chair, in which the seat frame, back frame, a pair of arm rests and the braces supporting the front ends of the arm rests are pivotally connected with each other so as to form adjustable quadrilaterals, one on each side of the chair.

It is an object of our invention to provide means whereby the coacting parts of such a folding arm chair can be locked in different relative positions in such manner that a simple movement imparted to certain of the coacting parts enables these particular parts to be displaced relatively to others and, on being released, to be locked automatically in the new position.

According to this invention the locking of these parts in an unlimited number of different relative positions is effected by way of a clamping means which replaces the pivotal connection of two adjoining parts in one of the four corners of the adjustable quadrilaterals. By rendering one of these pivotal connections immovable, the entire quadrilateral becomes immovable, and the several parts of the chair are fixed in the position imparted to them. By providing locking means operative by a mere frictional clamping action dependent on the angle between the two parts, it is possible to lock the two parts, and with them also the other parts of the movable quadrilaterals in different positions.

In the drawing affixed to this specification and forming part thereof a number of folding arm chairs and the means according to this invention for automatically fixing and holding coacting parts of such chair in their relative positions are illustrated diagrammatically by way of example.

In the drawing:

Fig. 1 is a perspective view of such chair in unfolded condition, while

Figs. 2 and 3 are a plan view and side elevation, respectively, of the same chair in folded condition.

Figs. 4 and 5 are perspective views, drawn to a larger scale, of the means for locking coacting parts of this chair in different positions.

Figs. 6 and 7 are side elevations, in different relative positions of the parts.

Fig. 8 is a perspective view of another folding chair in operative position, while

Figs. 9 and 10 illustrate on a larger scale and in two different operative positions the means

for locking coacting parts of this chair in different positions.

Referring to the drawing and first to Figs. 1—5, 1 are the side members of the seat frame and 2 is the cross bar connecting their front ends. 3 are the side members of the back and 4 are the rear legs, which are pivoted, similarly as the back, to the side members 1 of the seat, being connected by a cross bar 16. 5 are the arm rests 10 pivoted to the back and having the fore legs pivoted to their front ends, these legs being connected by a cross bar 7 and forming braces supporting the front ends of the arm rests. The seat frame, back frame, arm rests and braces on each side of the chair being movably connected with each other form an adjustable quadrilateral.

8, 9 are pins or bolts fixed to the fore legs and extending inwardly through slots 9 formed in the side members 1 of the seat frame. 10 are abutments of angular configuration fixed to the fore legs 6 and spaced from the pins 8 a distance, which is greater than the distance between the bottom wall of a slot 9 and the bottom edge of the side member 1, i. e. the thickness of the part 12 (Fig. 4) of the side member, in which this slot is provided, so that the part of the side member confined between the slot and the bottom edge can be shifted longitudinally between the bolt 8 and abutment 10, when the fore legs 6 extend at right angles to the side members 1. On the other hand, when the fore legs extend at an obtuse angle to the side members 1 and the abutments 10 are applied against the bottom sides of the side members, these latter are clamped between the abutments 10 and bolts 8, as shown in Fig. 1. Obviously the weight of a person seated on the canvas web 13 extending between the cross bars 2 and 14, this latter connecting the top ends of the back frame 3, in tending to enlarge the angle between the side members 1 and fore legs 6 will force the abutments 10 against the side members 1 and thereby strengthen the clamping effect. On the other hand a mere raising of the arm rests 5 will cause the bolts 8 to slide freely in the slots 9, so that then the chair can be folded up easily. This locking effect is further increased by the leaning back of the person sitting in the chair, whereby the back frame 3 is turned back and pulls, by way of the arm rests 5, the top ends of the fore legs 6 to the rear.

As shown in Figs. 6 and 7, the bolts 8 and slots 9 may be replaced by other abutments acting on the tops of the side members. In Fig. 6, 17 is a freely movable side member, 18 a freely movable

fore leg, 19 an abutment similar to the part 10 in Fig. 1, but consisting of a lath acting as a check and extending across the front faces of the pair of fore legs. 20 is another lath acting as a check and extending across the rear faces of the two fore legs, however above the two side members 17 and the two laths are spaced a distance which is greater than the thickness of the side members 17. Thus here again the fore legs are free to be shifted into the vertical position and beyond it until a weight acting on the side members 17 creates the tendency of enlarging the obtuse angle between the parts and thereby forcing the check 19 against the underside and 20 against the top side of the side members.

A similar locking means is provided in the folding chair of Fig. 8, which is however distinguished from that shown in Fig. 1 by having a seat frame extending beyond the back and forming also the rear legs. Here the side members 21 of the seat frame are pivoted to the fore legs 22, which are pivoted again to the arm rests 23, the rear ends of which are pivoted to the back frame 29. The side members 21 of the seat frame, instead of being pivoted to the back frame, extend across and to the rear of the back frame, their rear ends forming rests 25 which replace the rear legs. The side members of the back frame extend below the side members 21 of the seat frame and their bottom ends are connected by a lath 26 extending underneath the two side members 21. Another lath 27 is fixed to the side members 29 of the back frame, however on the rear side thereof and above the seat members 21, which latter is thus confined between the members of the back frame 29 and the two laths 26 and 27.

Thus, when a person sits down on the seat of this chair, leaning back against the back frame, the lever action exerted by the top halves of the members 29, which turn around the pivot pins 28, will force the bottom ends carrying the lath 26 against the side members 21 from below and the lath 27 against the same members from above, at the same time pulling the arm rests to the rear, whereby the fore legs 22 are pulled

back also, being however prevented from turning too far, because the two laths 26 and 27 in locking the side members 21 between them prevent any further rearward movement of the back 20. Thus the laths 26 and 27 here act similarly with regard to the seat and back, as they did, according to Figs. 6 and 7 with regard to the seat and fore legs.

In order to be able to vary the relative angular position of the seat 21 and back 29 according to requirements, the seat bars 21 may be formed, on the undersides and near the back, with wedge faces 49 leading to plane faces 30. The height of the side bars 21 at the level of the faces 30 is materially greater than in front of the wedge faces 49 and therefore the back may be locked in as many different positions relative to the seat as are determined by this difference in height of the side bars 21. The two end positions and the largest and smallest angle are shown in Figs. 9 and 10 respectively.

Various changes may be made in the details disclosed in the foregoing specification without departing from the invention or sacrificing the advantages thereof.

We claim:

In a folding arm chair in combination, a seat frame, a back frame, a pair of braces supporting arm rests, said seat frame, back frame, arm rests and braces forming adjustable quadrilaterals at the sides, the members of each quadrilateral being pivotally connected to each other at three of the four corners of the quadrilateral, while the two parts meeting in the fourth corner are in permanent slideable engagement with each other, two checks fixed to different faces of one of the two parts meeting in the fourth corner of each movable quadrilateral and embracing the other of said parts, being spaced from each other by a distance sufficiently exceeding the thickness of said other part at the meeting point to allow relative displacement of the parts whenever they extend substantially at right angles to each other.
